HALVOR ANDRESEN, OF NEW YORK, N. Y., ASSIGNOR TO THE VACUUM MUFFLER CORPORATION, OF NEW YORK, N. Y., A CORPORATION OF NEW YORK.

MUFFLER.

1,351,985.

Specification of Letters Patent.

Patented Sept. 7, 1920.

Application filed May 24, 1917. Serial No. 170,626.

To all whom it may concern:

Be it known that I, HALVOR ANDRESEN, a subject of the King of Norway, and a resident of the borough of Manhattan, in the city of New York, county and State of New York, have invented new and useful Improvements in Mufflers, of which the following is a specification.

The invention relates to mufflers or other noise reducing mechanism for use with internal combustion engines or in fact for use with any engine or device that has an intermittent discharge into an atmosphere having a lower pressure than that of the discharge.

According to the present invention gases or fluids flowing from the engine pass into a tubular member, arbitrarily referred to as a longitudinally-extending tubular-casing member. In flowing through or from this tubular member the gases pass a member that in effect serves as a diaphragm which is substantially inclined toward the longitudinal axis of the tubular member. The diaphragm member approaches the inner walls of the tubular member so that there is provided only a narrow slit or passageway through which the gases pass. Said diaphragm member has been given the substantial inclination just referred to in order that the slit through which the gases pass may be of a greater length than would be the case if the diaphragm member extended at substantially right angles to the longitudinally extending axis.

It will be manifest that if the angle of inclination of the diaphragm member toward the longitudinally extending axis is sufficiently acute the cross-sectional area of the passageway or space defined by the interior walls of the tubular member on the one hand and the diaphragm member on the other hand can be made equal to the cross-sectional area of the tubular member. In other words, there will be no substantial restriction of the area of the passageway through the tubular casing member even though the diaphragm member is located in said tubular casing member. The passing of the gases through this narrow slit or passageway causes a more or less uniform flow or muffling of the gases through the muffler.

As illustrating certain embodiments of

the invention reference is made to the drawings forming a part of this specification, in which drawings—

Figure 1 is a longitudinal sectional view of one form of muffler.

Fig. 2 is a view taken as along the line 2—2 of Fig. 1 looking in the direction of the arrows.

Fig. 3 is a view taken as on the line 3—3 of Fig. 2, looking in the direction of the arrows.

Fig. 4 is a longitudinal sectional view of another form of muffler.

Fig. 5 is a view taken as on the line 8—8 of Fig. 4 looking in the direction of the arrows.

Fig. 6 is a longitudinal sectional view of another form of muffler.

In the form shown in Fig. 1 the longitudinally extending casing member or tubular member is designated by 1 and to this there is secured, as by means 2, a member 3 that serves as a diaphragm member. The particular portion of the member 3 which serves as the diaphragm is that designated by 4, 5, 6, 7, 4. This member 3 approaches, as will be manifest from an inspection of Fig. 2, the inner wall or walls of the tubular member 1 leaving, however, a relatively narrow and long space 8. The width b of this space is shown in Fig. 2 and the length 85 thereof, it will be observed, is the elliptical peripheral portion 4, 5, 6, 7, 4. The width b shown in Fig. 2 has two millimeters or less, as will hereinafter appear. The rear side of the member 3 tapers to a point so that there can be a gradual expansion of the gases after they pass the diaphragm, and in the construction shown in Fig. 1 there is also provided a spiral deflector 9. At the forward end of the diaphragm member 3 90 there is secured a member 10 which is the member referred to in some of the claims as the third member, although this member 10 might well be considered as a part of the diaphragm member 3 since it is secured to 95 said member 3, as by means of bolts and screws 11 and 12.

The members 3 and 10 are separated from each other a slight distance, as will be readily seen from an inspection of Fig. 3, and water is supplied to said space through openings 13 that are in a water supply pipe 14. The flow of water into this space can

in a way control and assist the flow of gases past the diaphragm member 3 and can also be employed to cool the gases.

In Fig. 4 the longitudinally extending casing member of the muffler is designated as 26 and there is held in place, by means of pins 27 and 28, the diaphragm member 29 that is inclined so as to make an acute angle with the longitudinally extending tubular portion 10 26. The member 29 provides the diaphragm which is elliptical in form and which is designated by 30, 31, 32, 33, 30. In order that the gases after flowing past the diaphragm may expand more or less uniformly there has been 15 provided inclined walls 34, 35.

According to the construction shown in Fig. 6 the longitudinally extending casing member may be considered to comprise an outer casing member 36 and an intermediate 20 casing member 37. Passageways 38 are provided so as to permit the flow of some of the gases from the interior of the intermediate casing member 37 to the space between said intermediate casing member 37 and the exterior 25 casing member 36. The diaphragm member is designated as 39 and is held in place as by pins 40 and 41. The forward end of the member 39 provides the diaphragm portion 42, 43, 44, 45, 42 that approaches the 30 terminal of the intermediate member 37. The terminal of the intermediate member 37 may be considered as providing a second diaphragm member that is associated with the filler 46 secured to the interior of the exterior 35 casing member 36 by the pins 40 and 41. That part of the intermediate member 37 which may be considered as a diaphragm member is designated as 47, 48 and 49; only one-half of this intermediate member and 40 casing member are shown, as Fig. 6 is a sectional view. At the forward end of the diaphragm member 39 there may be secured in any suitable manner a member 50 which is referred to in the claims as the third member 45 of the muffler and this member 50 may be spaced from the member 39 in a similar manner to that in which the corresponding members are spaced in Fig. 1. In Fig. 6, however, these members are shown as integral 50 and part of the same construction. Within the delivery end of each of the mufflers shown in Figs. 4 and 6 there is provided any suitable filler, such as a bundle of wire x , that is relied upon to further iron out the 55 explosive noises resulting from the outgoing gases. The bundle of wire may protrude from said delivery end in order that it may be cooled and so that it may cool the gases passing therethrough.

60 In all the forms shown it will be observed that the diaphragm providing portion in effect is substantially inclined toward the longitudinally extending axis of the member with which it is associated and that there is 65 provided between it and the tubular member

with which it is associated a relatively long narrow slit—or this might be a series of slits—through which the gases flow in passing through or from the muffler.

The construction of each muffler described 70 is such that the smallest area for the flow of gases through the muffler is the area between the inclined diaphragm on the one hand and the inner wall of the tubular member on the other. In Figs. 1, 4 and 6 the longitudinally 75 extending axis of the longitudinally extending tubular portion or member in which the corresponding diaphragm is located is indicated by α and the slope or acute angle which the diaphragm makes with this axis α is indicated by a . This angle a (Figs. 1 and 4) is approximately 15 degrees and if the area of the long narrow slot, which is defined between the diaphragm 3 of Fig. 1 and the diaphragm 29 of Fig. 4 on the one hand and 80 the corresponding longitudinally extending tubular portion within which the diaphragm is located on the other, is to be such that the smallest area for the flow of gases through the muffler is the area between said inclined 85 diaphragm and the inner wall of the corresponding tubular member, then it will be readily ascertained mathematically that the dimension b (which dimension b is the width of the slot or in other words the distance 90 between the diaphragm on the one hand and the inner wall of the longitudinally extending tubular member on the other) is approximately two millimeters or less in a construction of the size shown in said figures of the 95 drawing.

In the construction shown in Fig. 6 the long narrow slot can be considered to be formed of two concentric narrow slots, the inner edge of the inner concentric slot being 100 defined by the periphery of the diaphragm member 39 and the outer edge of the outer concentric slot being defined by the upper end of the filler 46; and the dimension b' 105 from the diaphragm to this filler may be considered as the width of the two concentric slots. In the form shown in Fig. 6 the angle a is approximately 25 degrees and if these two slots are to provide the smallest area for the flow of gases through the muffler then it 110 will be readily ascertained mathematically that in a muffler of the size shown in Fig. 6 the dimension b' is approximately three millimeters; in other words, the width of each 115 slot would be approximately one and one-half millimeters whereby the combined slots would approximate the three millimeters just referred to. It will be observed that the intermediate casing member 37 is tapered to a thin edge adjacent to the co-operating edge of the diaphragm 39 whereby the two slotted portions just referred to are 120 separated by a thin wall.

The long narrow slots which have been referred to are continuous and extend about 130

the entire periphery of the diaphragm as is readily seen from an inspection of the drawing, and I have found that in a muffler, wherein all the passageways through which 5 the exhaust gases must escape are long slots in which the breadth or width of the slots is two millimeters or less, there is a substantial muffling effect of the noise of the gases as they pass through the muffler, this probably 10 due to the expansion and cooling effect on the gases in passing through such narrow slots.

The improvements herein set forth are not limited to the precise construction and arrangement shown and described for they 15 may be embodied in various forms and modifications without departing from the spirit and scope of the invention.

What I claim is:

1. A muffler of the class described comprising in combination a longitudinally extending tubular member, and a member providing an inclined diaphragm, the outer portion of which diaphragm approaches approximately to within two millimeters of 20 the inner wall of the longitudinally extending tubular member but is spaced from said wall a sufficient distance to permit the flow of gases through the space between the longitudinally extending outer member and the 25 diaphragm.

2. A muffler comprising a casing having a longitudinally extending tubular portion and an inclined diaphragm secured to said casing, which inclined diaphragm extends 30 adjacent to the wall of the longitudinally extending tubular portion and makes an acute angle of approximately 15 degrees with the longitudinally extending axis of said tubular portion, the construction being such that 35 there is provided between the casing and the diaphragm a long continuous narrow passageway of two millimeters or less in width through which flow the gases passing 40 through the muffler.

3. A muffler of the class described comprising a longitudinally extending tubular member and a member providing an inclined diaphragm portion that approaches the wall of the longitudinally extending 45 tubular member so that there is defined between said members a narrow passageway of two millimeters or less in width.

4. A muffler of the class described comprising a longitudinally extending tubular member and a member providing an inclined diaphragm portion that approaches the wall of the longitudinally extending tubular member so that there is defined between said members a narrow passageway of approximately 50 two millimeters or less in width, the construction being such that the smallest area for the flow of gases through the muffler is the area between said inclined diaphragm and the wall of said tubular member.

5. A muffler comprising in combination 65 an outer member having therein an inclined diaphragm member for providing a relatively long narrow space through which gases flowing through the muffler must pass, a third member spaced from said diaphragm 70 member, and means for supplying water to the space between said third member and said diaphragm member.

6. A muffler of the class described comprising in combination a longitudinally extending casing member, a diaphragm member connected thereto and associated therewith so as to provide a relatively long narrow space between the interior wall portion and the portion of the diaphragm member 80 which is included in a plane that is substantially inclined to the axis of the longitudinally extending member, the construction being such that the passageway between said diaphragm member and said casing member 85 is otherwise substantially unobstructed, a third member arranged in spaced relation to the diaphragm member, and means for delivering water into the space between said diaphragm member and said third member. 90

7. A muffler comprising in combination a casing member, a diaphragm member associated therewith having located with the forward end thereof a third member spaced from the diaphragm member, means for supplying water into the space between said 95 third member and the diaphragm member, and a spiral deflecting member at the delivery end of the diaphragm member.

8. A muffler comprising in combination a 100 tubular casing and an inclined diaphragm member associated therewith which diaphragm member on the rear side thereof gradually decreases.

9. A muffler comprising a tubular member 105 and a diaphragm within the same, said diaphragm being spaced from the tubular member approximately two millimeters or less, all the gases passing through the said space between the two members of the mufflers. 110

10. A muffler in which the passageway through which the gases pass is defined between a tubular wall and an inclined diaphragm whereby there is provided a long continuous narrow slot between the diaphragm and the wall, the construction being such that the width of this slot is approximately two millimeters or less and also such that the smallest area for the flow of gases through the muffler is the area of said slotted 115 portion.

This specification signed and witnessed this 23d day of May, A. D. 1917.
